F. W. BROCKSIEPER, OF NEW HAVEN, CONNECTICUT, ASSIGNOR TO SARGENT & CO., OF SAME PLACE.

Design No. 3,689, dated October 5, 1869.

DESIGN FOR A DRAWER-PULL.

The Schedule referred to in these Letters Patent and making part of the same.

To all whom it may concern:

Be it known that I, F. W. BROCKSIEPER, of New Haven, in the county of New Haven, and State of Connecticut, have invented a new Design for Drawer-Pull; and I do hereby declare the following, when taken in connection with the accompanying drawing, to be a full, clear, and exact description of the same, and which said drawing constitutes part of this specification, and represents a front view.

This invention relates to a design for the ornamentation of the article of manufacture known to the trade as drawer-pulls, and such as are of shell form; and

The invention consists in the ornamentation of a drawer-pull, as fully shown in the accompanying photographic illustration.

I claim, as my invention—

The design for drawer-pull, as herein described and shown.

F. W. BROCKSIEPER.
